UNITED STATES PATENT OFFICE.

CHRISTOPHER J. MOGAN AND CHRISTIAN B. ANFINDSEN, OF CHARLEROI, PENNSYLVANIA.

BUNDLING-MACHINE.

1,261,589.

Specification of Letters Patent.

Patented Apr. 2, 1918.

Application filed January 30, 1917. Serial No. 145,397.

To all whom it may concern:

Be it known that we, CHRISTOPHER J. MOGAN and CHRISTIAN B. ANFINDSEN, citizens of the United States, and residents of Charleroi, in the county of Washington and State of Pennsylvania, have invented a new and useful Improvement in Bundling-Machines; and we do hereby declare the following to be a full, clear, and exact description thereof.

Our invention relates to bundling machines, for compressing into bundles and securing by tie bands such material as wire in coils, straight wire, rods, band iron and other articles. Heretofore the operations in preparing bundles of the above mentioned material were performed by hand. In bundling coil wire, particularly, two employees are generally needed, and the operation of stretching and twisting the tie band by pliers is necessarily slow and tedious labor, with resultant irregularity of bundle and great waste of tie material.

The invention is devised primarily for performing the above operations automatically, so as to give uniformity and rapidity to the steps of the operations, with uniformity of bundle and increased output.

A further object is to provide a machine which is adjustable to a wide range of bundle sizes, which may be employed as a single machine for some kinds of material, or arranged as a single unit in a machine comprising several such units for bundling long material, such as rods or the like.

A further object is to provide a machine of the above character in which the material is compactly pressed to form a symmetrical bundle having a tie band of minimum length.

The bundle so formed resulting in a saving of tie material and in bundle space for storing or shipping.

The invention consists in the novel construction, combination and arrangement of parts hereinafter described.

In the accompanying drawings, Figure 1 is a side elevation of the machine; Fig. 2 is an end elevation; Fig. 3 is a front elevation of one unit forming half of the machine; Fig. 4 is an enlarged vertical section of the upper portion of one half of the machine the section being taken on a line central with the

twister spindle, the twister being in elevation; Fig. 5 is a horizontal section on the line 5—5, Fig. 1; Fig. 6 is a vertical section showing the bundle elevating-jaw in a position carrying up the tie band; Fig. 7 is a like section showing the tie band ends brought together in position to be acted on by the twister; Fig. 8 is a like section showing the compressed bundle and the position of the twister in twisting the tie; Figs. 9, 10 and 11 are detail views of the mechanism for moving the ends of the tie band in position for engagement with the twister jaws; Figs. 12 and 13 are detail views of the holder for holding the cut tie band in position to be carried up around the bundle by the bundle elevating-jaw; Fig. 14 is an inverted plan view of the twisting jaws in closed position; Fig. 15 is an enlarged cross-section of a tied bundle.

The numeral 2 indicates the base or bed-plate of the machine and is shown as a portable machine with wheels 3. Upon the base plate is secured housings 4 which form the frame for supporting all of the mechanism of the machine except the power element which in the instance shown is a motor 5 on the bed-plate 2. These housings are in duplicate, right and left, and have like mechanisms which operate in unison, and in describing the invention, we will refer to only one side of the machine.

Situated between the housings on supports 6 is the bundle table 7. Referring now to Fig. 5, it will be seen that the table is formed of two sections connected by extension rods 8 and each section is adapted to slide on the supports 6 for adjustment to support various sizes of bundles. The machine is illustrated as arranged for bundling coils of wire, such a coil being indicated at 9. The table for bundling this kind of material is provided with the radial supporting rollers 10. One of the housings of the machine is adjustable on the bed-plate so as to adapt the machine for various diameters of coils, the adjustment being effected through a screw 11 anchored to the bed-plate and having engagement with a nut in the housing. The screw is adapted to be rotated by gearing 12 and hand-wheel 12^a. This is a well-known form of construction for an ad-

justable screw-feed for various purposes, and needs no further description in connection with this invention.

The loose coils of the wire are conveyed 5 to the machine on a power carrier 13 which is a simple type of endless conveyer of any suitable structure. The coils are delivered onto the table and pulled in position by the operator to be bound. In some cases, several 10 of such coils, if they are thin coils or coils of short length, are stacked on top of one another to be formed into a single bundle of commercial size.

Fig. 1 represents the machine with a loose 15 coil of wire resting on the table in position ready to be elevated by the upward movement of the compressor heads 15. The compressor heads of both sides of the machine moving in unison carry the coil up into engagement with fixed compressor-jaws 16, when at the completion of the up stroke, the tie band 9^a, which is also carried up with the bundle, is tightly twisted to bind the coil in compressed shape. Two of such bands are 20 applied simultaneously at one operation of the machine, and the bands are arranged diametrically opposite one another on the coil. At the down stroke of the compressor-heads, the bundle frees itself from the fixed 25 jaws and is lowered with the compressor-heads where it again rests on the table rollers in position to be rotated so as to present the bundle in a position for applying other bands; usually four bands are applied to a 30 coil of wire, the bands being arranged about 35 equally spaced.

One unit, or one-half of the machine as employed for coil material, may be used for bundling long straight material such as rods 40 or the like, by feeding the rods longitudinally onto the compressor-head for each band applied. Or, several of such units may be arranged so as to have their jaws in alinement, whereby all of the bands are 45 applied simultaneously. No illustration is shown of the units so arranged, but as hereinafter described, it will be seen that the mechanism of each unit is such as to permit the units to be arranged in line, or in a row, 50 and driven to act in unison by driving from a single shaft through bevel gear connections, as indicated in dotted lines at A in Fig. 1 of the drawing; and it is to be understood, and included as part of our invention 55 to have the units so arranged.

The mechanism for accomplishing the operations of the machine is as follows: A power-shaft 17 driven by the motor 5 or other suitable source of power drives 60 through sprockets and chain 18-18', a shaft 19, which, through direct bevel-gear connections 20, rotates the tie twister spindle 21. Spur-gears 22, shaft 23, and bevel-gears 24 drive a shaft 25 from which power is taken

for elevating and compressing the bundle. 65 Shaft 25 drives by pinion 26, a gear 27 on shaft 28. Movement for reciprocating the compressor-head is provided by connecting to the gear 27, a pitman 29, which connects by an arm 30 to a rock-shaft 31. A forked 70 arm 32 is secured to the rock-shaft, and connects by swinging link to a sleeve 33 on the compressor-head shaft 34. Referring to the enlarged view, Fig. 4, it will be seen that the compressor-head 15 is mounted on a screw 75 35 engaging the sleeve 33, and said screw provides means for adjustment to vary the length of the travel of the head for compressing various thickness of bundles, and for adjusting the head to position with different sizes of jaws employed, the jaws being of various cross-sectional shapes, and are removable. Rotation of gear 27 acts through the downward stroke of the pitman to elevate the compressor-head to carry up the 80 bundle and compress it. At completion of the downward stroke, the arm 30 which is provided with a catch piece 30^a, engages a spring-held latch or holding-stop 36, which holds the elevated bundle momentarily at 85 the beginning of the upstroke of the pitman, while the tie-band is twisted. The delay period for holding is effected by providing "play" at the connection of the pitman and arm, such as the elongated eye bearing 87 90 for the pin 37^a. The pitman is provided with a tripper 38 which is so positioned, that, the idle movement of the pitman on the upstroke brings the tripper into engagement with the spring-latch, freeing the arm of the 95 100 rock-shaft, and allowing the bundle to be lowered as the upstroke of the pitman continues. When the compressor-head is in its lowered position, the tie material is fed into the machine to a position beneath the bundle and cut off. The tie material is in a coil or on a reel, not shown, and passes through tension rolls before entering the machine. The tie is then carried by the bifurcated 105 jaws of the compressor-head with the bundle to the elevated position, and the tie is applied by a twister. 110

Means for feeding the tie material into position to be cut off and to be engaged by the compressor-head comprise geared feed-rolls 40 and 41. The shear for cutting the tie is indicated at 42. The tie as fed to position beneath the bundle lies above and out of engagement with the normal low position of the compressor-head jaws, and means, such as the holder 43 is provided for supporting the tie after being cut by the shear. This holder consists of blocks 44 and 45 supported on a bracket 46. The block 45 is yieldable and is spring-held, so as to 115 120 form a clamp with the other block for gripping the wire, details of which are clearly 125 shown in Figs. 12 and 13.

Rotation of the feed-rolls is made intermittent to permit return of the compressor-head to a position beneath the table, as shown in full lines in Fig. 4, before a new tie is fed forward. Also, the length of time of feed is controlled to provide the proper length of tie for various bundles. The following mechanism is employed to accomplish this result: Shaft 28 driven by gear 10 27 is provided with an arm 50 which carries a spring pressed pawl 51 which is held in engagement with a ratchet-wheel 52 loosely journaled on said shaft. Said ratchet drives a gear 53 which meshes with a gear 54 on 15 the shaft 55 to which the top feed-roll 40 is secured. Means for disengaging the pawl from the ratchet when the proper length of tie has been fed forward, consists in providing a guide ring segment 56 mounted on the 20 housing concentric with shaft 28 and having an adjustable end to form an open space 56^a between the other end of the ring segment. The inside diameter of the segment forms a track adapted to engage a roller 25 51^b of the pawl, which rocks the pawl on its pivot out of engagement with the teeth of the ratchet. The open space of the segment permits the pawl to move to its natural spring-pressed position to engage the 30 ratchet. The length of the open space determines the length of the travel, or the time in which the feed-rolls are rotated. This ring segment is provided with a movable section 56^b which may be adjusted to lengthen or 35 contract the open space 56^a of the ring, to shorten or prolong the time of engagement of the pawl with the ratchet to feed the tie band for various lengths.

Shaft 28 also provides power for operating the cutting shear 42. The shear blade is secured to a cross-head or block 57 secured to rods 57^a which reciprocate through the shear block 58. The upper ends of the rods are connected by a cross-head 57^b and link 45 57^c to an arm 59^a of a bell-crank 59 journaled on a shaft in the frame. The other arm 60^a of the bell-crank engages with a cam 60 on the shaft 28. The cam is adjustably mounted on the shaft to permit 50 setting to different positions for varying the time period of "throw" for moving the shear to cut different lengths of ties.

Mechanism for binding the compressed bundle is clearly shown in the vertical sectional view, Fig. 6. This mechanism includes the rotating spindle 21 which has the head 21' to which is pivoted in oppositely disposed position, a pair of jaws 21^b. These jaws are connected by links to a sliding member 21^c, which is adapted to reciprocate on the spindle, and forms with the links a toggle-joint for moving the jaws to open and closed position. Figs. 6 and 7 represent the jaws in open position, and Fig. 8

in the closed position. The sliding member 65 is reciprocated by a forked arm 70 journaled to the member to permit of rotation of the member with the spindle. Arm 70 is secured to a rock shaft 71, which is rocked by cams 72 and 73, secured to shaft 28, said 70 cams engaging the rollers of arms 74 and 75, respectively, secured to shaft 71.

During the feeding of the tie band, and while the compressor-head is elevating the bundle, arm 74 is engaged by the "delay" 75 face 72 of cam 72, which keeps the sliding member elevated and the tie gripping-jaws open to receive the ends of the tie band. The tie band is stripped from the holder 43 as the compressor-head moves up, and is forced 80 into the cavity 15^a of the jaw of the compressor-head, as clearly shown in Fig. 6. When the bundle has been moved to compressed position, the free spreading ends of the tie band are brought together as in Fig. 85 7, so as to be engaged by the gripping-jaws of the twister. Means for closing the ends of the tie consist of two horizontal sliding plates 80 and 81 mounted to slide in guides 80^a on the fixed compressor jaw, as clearly 90 shown in Figs. 9, 10 and 11. These slides are actuated by a cam 82 on the shaft 28. A roller arm 83 engaging the cam is adapted to slide in a fixture fast to the housing and has a rack 84 which rotates a pinion 85. Pinion 85 through rack engagement 86 and arm connection 87, reciprocates slide plate 80. Plate 81 is provided with a rack 88 which meshes with a pinion 89 fast to shaft 90 to which pinion 85 is secured. Reverse 100 direction of motion of the plates is effected by locating the pinions between the slide racks. The plates are returned to their open positions by means of a spring 83.

When the bundle has been moved to compressed position, cam 72 has moved to free the holding arm 74 and at the same time, cam 73 engages the roller of arm 75, moving the arm up and rocking the shaft to lower the sliding member 21^b. The sliding member in lowering, closes the tie gripping-jaws. These jaws have V-shaped gripping faces 21^c and in closing draw the ends of the wire central with the rotating spindle in which position the revolving jaws twist the bands 110 tightly to bind the bundle. The jaws remain closed while the arm 75 engages the delay face 73^a of cam 73.

From the foregoing description of the machine and its operations it will be seen that 120 bundling of material may be done rapidly and with uniformity of bundles, and the wide range of adjustment brings many different sizes of bundles within the scope of the machine. While the machine is designed 125 primarily for bundling coiled material such as coil wire or the like, of substantially circular cross sectional shape of bundle, the

invention is by no means restricted thereto. It will be apparent that material may be bound into bundles of various cross sectional shapes by simply changing the shape of the 5 recess in the compressor jaws, and making the jaws in the fixed compressor-head 16 removable, in the same manner as they are removable in the lower compressor-head. Also, it will be apparent that when the units of 10 the machine are used for bundling long straight material such as rods or the like, other forms of table or bundle support may be employed without departing from the principle of my invention.

15. What we claim is:

1. In a bundling machine, the combination of a bundle compressor comprising fixed and movable compressor heads, a bundle support for positioning the bundle between the heads 20 and out of engagement therewith, tie-feeding mechanism, a drive-shaft, connections between said shaft and said movable head for reciprocating the head, a tie-twister, and connections coöperatively associated with 25 said twister and said first connections for actuating said twister.

2. In a bundling machine, the combination of a bundle compressor comprising fixed and movable compressor heads in vertical alignment, a bundle support for positioning the 30 bundle between the heads and out of engagement therewith, tie-feeding mechanism, a drive-shaft, connections between said shaft and said movable head for reciprocating the head, a tie-twister, and connections coöperatively associated with 35 said twister and said first connections for actuating said twister.

3. In a bundling machine, the combination 40 of a bundle compressor comprising fixed and movable compressor heads, a bundle support for positioning the bundle above the movable head, tie-feeding mechanism, a drive-shaft, connections between the compressor and said shaft for operating the 45 compressor and the tie-feeding mechanism, a tie-twister, and connections between said first connections and the twister for controlling the twister.

50. 4. In a bundling machine, the combination of a bundle compressor comprising fixed and movable compressor heads, a bundle support for positioning the bundle above the movable head, tie-feeding mechanism for feeding 55 the tie in position to be engaged by the movable head, a drive-shaft, connections between the compressor and the tie-feeding mechanism, a tie-twister, and connections between said first connections and the twister for controlling the twister.

60. 5. In a bundling machine, the combination of a bundle table, tie-feeding mechanism, a drive-shaft, compressor mechanism

for elevating and compressing the bundle, 65 connections between said shaft and said compressor mechanism for actuating the feeding mechanism, a tie-twister, and connections between said shaft and said compressor mechanism for actuating the twister. 70

6. In a bundling machine, a table for positioning the material to be bound, tie-feeding mechanism, a continuously rotating drive-shaft, a bundle compressor for elevating and compressing the bundle, connections 75 between the shaft and the compressor for reciprocating the compressor, connections from said first connections for intermittently operating the tie-feeding mechanism, a tie-twister and connections from 80 said first connections for controlling the twister.

7. In a bundling machine, a table for positioning the material to be bound, a continuously rotating drive shaft, tie-feeding 85 mechanism, a bundle compressor, connections between the shaft and the feeding mechanism for feeding the tie beneath the bundle, a tie-shear, connections between the shaft and the compressor for elevating the 90 compressor to compress the bundle, said connections coöperatively mated with connections for operating the shear, a tie-twister actuated by said shaft, and connections between the twister and said second 95 connections for controlling the twister.

8. In a bundling machine, a bundle-table for positioning the material to be bound, a bundle-compressor comprising fixed and movable compressor heads, tie-feeding 100 rolls for feeding the tie beneath the bundle above the movable compressor head, a tie-shear, a drive-shaft, mechanism operated by the shaft for elevating the movable head and for operating said shear, a tie-twister, means for holding the bundle in compressed 105 position while the tie is twisted, and means actuated by said second mechanism for controlling the twister.

9. In a bundling machine, the combination 110 with the bundle-compressor and binding mechanism, of means for operating the compressor to elevate and compress the bundle, means for holding the compressor elevated at completion of its compressing stroke, means for operating the binding mechanism during the holding period to bind the bundle, and a tripper actuated by said first means for tripping the holding means to release the compressor at completion 115 of the binding operation.

10. In a bundling machine, the combination 120 with a plurality of bundle-compressors for elevating and compressing the bundle, a drive-shaft, connections from the shaft 125 for operating the compressors in unison, binding mechanism for each compressor, connections from the shaft for simulta-

neously operating the binding mechanism, controlled by said first connections.

11. In a bundling machine for bundling coils of wire or the like, a pair of bundle-compressors oppositely disposed, a table for positioning the bundle substantially central to the compressors, tie-feeding mechanism, means for operating the compressors in unison to compress the bundle, binding mechanism, and means for operating said mechanism for applying a tie to bind the compressed bundle.

12. In a bundling machine for bundling coils of wire or the like, a pair of bundle-compressors oppositely disposed, a bundle-table for positioning the bundle, tie-feeding mechanism, a drive-shaft, binding mechanism, connections from the shaft for operating the compressors in unison to compress the bundle, and connections from the shaft for operating the binding mechanism to secure the tie to bind the compressed bundle.

13. In a bundling machine, the combination with a plurality of bundle-compressors, said compressors comprising fixed and movable compressor heads, a bundle-table for positioning the bundle above the movable heads, means for operating the movable heads in unison to elevate and compress the bundle, binding mechanism, and means for operating the binding mechanism co-operatively associated with the elevating and compressing means.

14. In a bundling machine for bundling coils of wire or the like, a pair of bundle-compressors oppositely disposed, a bundle-table for rotatably positioning the bundle above the compressors, tie-feeding mechanism for feeding the tie beneath the bundle, means for operating the compressors in unison to elevate and compress the bundle, and binding mechanism for binding the tie to secure the compressed bundle.

15. In a bundling machine for coils of wire or the like, the combination with duplex compressing and binding mechanism, said compressing mechanism comprising fixed and movable compressor heads in vertical alinement, a bundle-table for rotatably positioning the bundle between the fixed and movable heads, means for operating the movable heads in unison to elevate the bundle and compress it, and means for operating the binding mechanism to bind the compressed bundle.

16. In a bundling machine, the combination of a bundle compressor comprising fixed and movable compressor heads, a bundle-table for positioning the bundle between the heads, tie-feeding mechanism for feed-

ing the tie into position to be engaged by the movable head, a tie-twister, means for operating the movable head to carry the tie into engagement with the bundle and to compress the bundle, and connections between said means and the twister for operating the twister.

17. In a bundling machine, the combination of a bundle compressor comprising fixed and movable compressor heads in opposed relation, a bundle table for supporting the bundle in binding position free of the heads, tie-feeding mechanism for feeding the tie into position to be engaged by the movable head, a tie-twister, means for operating the movable head to apply the tie to the bundle and to carry the bundle off of the table to compress it against the fixed compressor head, and connections between said means and the twister for twisting the tie.

18. In a bundling machine for coils of wire or the like, the combination with duplex compressing and binding mechanism, said compressing mechanism comprising fixed and movable compressor heads, a bundle table, and means comprising radial rollers for positioning the coil bundle on the table between the fixed and movable compressor heads to be engaged by said heads diametrically opposite on the coil, means for operating the movable heads in unison to elevate the bundle and compress it in the fixed compressor heads, and means for operating the binding mechanism to bind at the point of compression.

19. In a bundling machine, a bundle-table for positioning the material to be bound, a bundle-compressor comprising a fixed head disposed above the table, and a movable head for engaging the material from below, tie-feeding rolls for feeding the tie to be engaged by the movable head, a tie-shear, means for holding the sheared tie, a drive-shaft, mechanism operated by the shaft for elevating the movable head and for operating the shear, a tie-twister, means for holding the bundle in compressed position while the tie is twisted, means operated by said mechanism for controlling the twister, and means co-operatively associated with said mechanism for lowering the compressor head and intermittently moving the feed-rolls.

In testimony whereof, we the said CHRISTOPHER J. MOGAN and CHRISTIAN B. ANFINDSEN, have hereunto set our hands.

CHRISTOPHER J. MOGAN.
CHRISTIAN B. ANFINDSEN.
